GOLF TEE

Bruce A. Coffin, Peabody, Mass.

Application April 7, 1944, Serial No. 529,916

3 Claims. (Cl. 120—83)

This invention relates to a golf tee.

In the playing of golf the score which is made by each player for each hole is usually written upon a card. A pencil is carried for writing the score on the card. The score is usually written down for one hole immediately after finishing play at the green for the hole or while walking from the green of the last hole to the tee of the next hole or on the tee of the succeeding hole. Frequently a pre-made tee is used for the ball to be driven such as a made wooden or plastic tee for supporting the ball prior to driving.

One of the objects of this invention is to utilize a tee made of wood, plastic or any other rigid material as a means for writing the score which has been made by the different players for the previous hole upon a card.

Another object of this invention is to utilize a made tee in exactly the form that it is at the present time and additionally apply to this tee some marking means by which the tee may be utilized as a pencil for the score card.

Another object of the invention is to provide a marking substance which will not be dislodged upon the tee being placed into the ground.

Another object of this invention is to arrange a sufficient amount of marking material so that the same will last for substantially the life of the tee upon which it is applied, so that so long as this tee is used as a support for the ball to be driven the tee may also be used as a marking device upon the score card.

With these and other objects in view, the invention consists of certain novel features of construction, as will be more fully described and particularly pointed out in the appended claims.

In the accompanying drawing:

Fig. 1 illustrates the tee as supporting a golf ball, the ground being illustrated in section;

Fig. 2 illustrates in section a tee and fragmentally a nozzle for applying a coating to the pointed end of the tee;

Fig. 3 is a sectional view illustrating somewhat diagrammatically the dipping of the tee in a liquid;

Fig. 4 is a sectional view of the tee with the marking coating applied thereto.

In proceeding with this invention I deposit upon the pointed end of the tee a coating and permit this coating to sag toward the point end to provide a thickened surface of the coating at this location as the coating dries upon the point of the tee.

With reference to the drawing 10 designates a

tee which may be formed of wood, plastic, or any suitable rigid material, which has a cupped enlarged head 11 for the reception of a golf ball 12 to support the same above the ground 13 into which the tee may be positioned as illustrated in Fig. 1. This tee 10 has deposited upon its pointed end 14 a marking substance, as designated at 15 in Fig. 4, of carbon, lead, graphite or the like with a binder.

This deposit may occur from a spray nozzle 16, as shown at 17 in Fig. 2, or the deposit may occur by the tee 10 being supported in a rack 18, as shown in Fig. 3, and dipped in liquid 19 consisting of the same material in a trough 20. In either case after the deposit of the material occurs either from spraying or from dipping, the tees are suspended in a rack such as shown at 18 so that the liquid which has been deposited will sag downwardly to form a concentration as at 21 on the end of the tee in a drop type of accumulation as the solvent evaporates, thus leaving a thickened surface, as at 22, shown in Fig. 4 on the pointed end 14 of the tee which will be a sufficient accumulation of marking material so that the tee may be used for marking upon a score card the few numbers which are required in the playing of the game.

A tee such as indicated for supporting the ball for driving soon becomes lost or broken but the marking substance will be in a sufficient amount so that such marking as is required for the length of the time the tee ordinarily lasts will be sufficient.

The marking substance and the binder will be such as to harden sufficiently so that even if the pointed end of the tee is pressed into the ground and frictioned with the ground the marking substance will not be worn off to any material extent, the same being harder than the surrounding ground into which it is pressed.

I claim:

1. A golf tee pointed at one end and having a coating at the pointed end of a substance capable of marking on a piece of paper or the like.

2. A golf tee pointed at one end and having a coating at the pointed end of a substance capable of marking on a piece of paper or the like, said coating being in the form of a drop type of accumulation of liquid at said end.

3. A golf tee pointed at one end and having attached at said end and on the surface thereof a marking substance.

BRUCE A. COFFIN.
